JAMES D. MOORE, OF BOSTON, MASSACHUSETTS.

HEATER.

Application filed April 4, 1927. Serial No. 180,630.

This invention pertains to stoves and more particularly to oil heaters of portable type. Such stoves or heaters usually comprise a base containing an oil tank upon which the burner is mounted and a cylindrical vertical drum carried by the base and housing the burner, such drum usually being closed at its top. Commonly the drum is provided with a plurality of apertures in its side wall near its upper end for the escape of the heated air and gases arising from the burner.

In a stove thus constructed the column of heated air which rises from the burner tends to contract in diameter as it ascends so that it fails to give up its heat to the side walls of the drum, while the hot air which escapes at the upper part of the drum also tends to form a vertical column directly above the heater. The result of this action is that but little heat is radiated or dissipated laterally from the heater, and the air of the room or apartment in which the heater is placed is unduly heated at its upper portion before the lower parts of the room are appreciably warm.

Oil heaters as ordinarily constructed are limited as to the size of burner employed, it being found by experience that if the diameter of the burner be increased beyond a fairly definite maximum, it is difficult to control the flame so as to prevent smoking, whereas if the diameter of the burner be decreased below this limit, the heat given out is correspondingly decreased.

I have ascertained that the smoking and uncertainty of operation of the burner when increased beyond a certain diameter is apparently due to the abnormal heating of the burner itself which results in unduly rapid evaporation of oil and evolution of gas and consequent flaring and smoking of the flame, and that this difficulty can be substantially overcome and the diameter of the burner increased beyond the usually accepted limit by protecting the central part of the burner from the direct and reflected heat of the flame. This result is readily attainable in conjunction with the means herein provided for controlling the heat radiated from the side walls of the heater.

My present invention has for its principal object the provision of a heater of the character described so designed that the greater portion of the heat will be radiated

from the side walls of the drum, thereby warming the lower parts of the room much more quickly than is possible with an ordinary oil heater, and of such character that the burner may be made of substantially any desired diameter without causing the flame to flare or smoke.

In the accompanying drawings a preferred embodiment of the invention is illustrated by way of example,

Fig. 1 being a side elevation partly in section showing the improved heater;

Fig. 2 is a horizontal section on the line 2—2 of Fig. 1;

Fig. 3 shows, in vertical section, the upper part of a heater of slightly modified form and illustrates the path of the heated currents of air;

Fig. 4 is a vertical section to smaller scale illustrating a further modification; and

Fig. 5 is a similar view but illustrating a heater of ordinary type and showing the usual course of the air currents therein.

Referring to Fig. 5 the numeral 1 designates the upper part of the base of a heater of usual type, such base supporting the drum 2 having the cover member 3 at its upper end. The burner 10 is carried by the base and is disposed axially of the drum 2. The drum is shown as provided with series of openings 4 near its upper end adapted to permit the escape of heated air and gases rising from the burner.

In this view the usual path of the air currents has been indicated in broken lines, and it may be noted that while the column of air flares outwardly immediately above the burner, it rapidly contracts in diameter as indicated at 5 so that its heating effect is concentrated at the central part of the cover, there being a relatively large space between the upper part of this column of air and the side walls of the drum.

The column of heated air strikes the under side of the cover 3 and is deflected outwardly through the holes 4 and after passing the edges of the cover 3 again ascends in a column of diminishing diameter as indicated at 7. With this arrangement comparatively little heat is radiated from the side walls of the drum since the column of air rising from the burner comes into contact with the drum only at the upper part of the latter.

Referring now to Figs. 1 and 2, the base of the improved heater is indicated at 8,

such base supporting the drum 9. This drum is preferably, although not necessarily, provided with corrugated walls thus greatly increasing its radiating capacity. An increase 5 in the radiating surface of the drum of 60% beyond that of the usual drum may readily be obtained in this way.

The base 8 supports the circular burner 10 which may be of usual construction and 10 which is coaxial with the drum. The drum is provided with perforations 11 extending for a considerable distance down from its upper end.

As here shown, these perforations are 15 formed in the outermost portions of the corrugations of the drum, and they are arranged in circumferentially extending series, the series being spaced vertically as may be desired. Preferably these perforations extend 20 down at least midway of the length of the drum.

The drum is provided with a cover 3, preferably imperforate, and within the drum a deflector is arranged. This deflector preferably comprises a main or body portion 13 of 25 truncated conical form with its smaller end directed downwardly. This deflector is supported in any desired manner, preferably from a flange at the upper end of the drum. 30 The deflector member 13 terminates at a substantial distance above the burner, preferably at about the region of the lowermost series of the perforations, the lower end of the deflector being closed. As here shown the 35 lower end of the deflector member 13 is closed by means of a secondary deflector element 14 of truncated conical form, concentric with the burner 10 and secured to the lower edge of the element 13 in any desired manner. 40 The lower end of the member 14 rests upon the top of the burner 10 with heat insulating means interposed, if desired, and thus protects the central part of the burner top from 45 radiant heat.

The space 15 between the main member 13 of the deflector and the inner surface of the drum is thus of annular form and of increasing radial width from the region of the lowermost perforations toward the upper 50 part of the drum. In Fig. 3 a slight modification is illustrated, the base 8^a supporting the burner 10 housed in the drum 9^a. This drum is shown as without corrugations, but the employment of such corrugations is optional. In this form the deflector comprises the upper portion 13^a and the lower portion 14^a, the latter being conical and having an apex just above the top of the burner.

In the arrangement shown in Figs. 1 and 3 60 the innermost filaments 16 of heated air rising from the burner engage the conical surfaces of the deflector and follow along the latter until they reach the upper part of the annular space where they come out through 65 the uppermost series of perforations. The in-

termediate filaments of air follow generally the same course but pass out through series of perforations lower down the drum so that the outermost filaments 17 may be considered in general to pass out through the lowermost 70 series of perforations.

The entire body of heated air is thus brought into very close contact with the walls of the drum, heating the latter throughout the great part of its length so 75 that it forms an efficient source of radiant heat, and then passes laterally into the room. Such heat as may be absorbed by the deflector member is likewise radiated outwardly and assists in heating the walls of the drum 80 while the air which passes out through the perforations in the drum, being distributed longitudinally of the drum, acts in a much more efficient manner to heat the air in the immediate vicinity of the heater than is true 85 of the ordinary oil heater in which the air escapes only at the top.

In Fig. 4 a further modification is illustrated in which the burner 10 is housed by a drum 9^b and in which the deflector consists of a single continuous member 13^b of inverted truncated conical form with its smaller end resting on the burner top and concentric therewith. If desired, this deflector may be supported by the burner top 90 and need not extend to the top of the drum.

While a deflector of generally conical or truncated form is preferable, I contemplate that deflectors of other types might be employed provided they direct the heated 100 column of air outwardly in an annular stream into intimate contact with the wall of the drum throughout a substantial portion of the length of the latter, and particularly if at the same time they govern the 105 heat absorbed by the central part of the burner top.

I also contemplate that a drum without perforations might be found useful to some extent and that the perforations in the drum 110 might be arranged otherwise than as here shown without sacrifice of the principle which underlies the invention.

I claim:

1. A heater of the class described comprising a burner, a vertical cylindrical drum housing the burner, said drum having openings in its side walls, and a deflector within and concentric with the drum, said deflector being of less diameter than the drum to 115 provide an annular space between it and the drum, the deflector extending down from an imperforate top cover of the drum substantially to the top of the burner.

2. A heater of the class described comprising a burner, a vertical cylindrical drum housing the burner, said drum having openings in its side wall, and a deflector comprising an inverted truncated conical body portion suspended from the upper part of 120 125 130

the drum and concentric therewith, an imperforate cover on the upper end and a deflector element attached to the lower end of the body portion, said deflector extending 5 downwardly from the upper end of the drum nearly to the burner.

3. A heater of the class described comprising a burner, a vertical cylindrical drum housing the burner, circumferential series 10 of openings in its side walls, an imperforate cover for the drum, and a deflector concentric with the drum, the deflector comprising a body portion of truncated conical form having its larger end in the upper part of the 15 drum, the deflector extending from the upper part of the drum substantially to the top of the burner.

4. A heater of the class described comprising a burner, a vertical cylindrical drum housing the burner, said drum having corrugated side walls provided with perforations, and a deflector disposed within the drum, said deflector extending substantially from the top of the drum to the burner and comprising a cover member, serving also as the 20 top of the drum, an upper body portion of inverted truncated conical form, and a lower portion of inverted truncated conical form, said deflector being concentric with the drum and providing an annular space between it and the inner surface of the drum. 25

Signed by me at Boston, Massachusetts, this 28th day of March, 1927.

JAMES H. CAMPBELL.
